UNITED STATES PATENT OFFICE.

WILLIAM H. PIKE, JR., OF SOUTH ORANGE, NEW JERSEY, ASSIGNEE, BY MESNE ASSIGNMENTS, TO BURROUGHS ADDING MACHINE COMPANY, OF DETROIT, MICHIGAN, A CORPORATION OF MICHIGAN.

ADDING AND RECORDING MACHINE.

1,094,470.

Specification of Letters Patent. Patented Apr. 28, 1914.

Application filed January 29, 1907. Serial No. 354,779.

To all whom it may concern:

Be it known that I, WILLIAM H. PIKE, Jr., a citizen of the United States, and resident of South Orange, Essex county, State 5 of New Jersey, have invented certain new and useful Improvements in Adding and Recording Machines, of which the following is a specification.

This invention relates to improvements in 10 adding and recording machines and has for its object to provide a machine which is adapted for more extended or varied uses than machines of the same general character heretofore commonly in use. Such machines 15 have been adapted for printing items in a plurality of parallel columns, the items recorded in each column being accumulated on accumulating devices as they are recorded. For many purposes, however, it is desirable 20 to record a series of numbers in a column without the accumulating devices being affected by such recording. For instance, in compiling certain records, it is desirable to arrange in one column the designating or 25 indicating numbers of a series of articles, and in a second column the values of articles, the value of each article being on the same line as the number designating that article; and it is desirable that the value items be 30 accumulated in order that the total thereof may be readily ascertained at any time. Or again, in keeping a record of disbursements, the numbers of the vouchers or payment 35 orders would appear in one column and the values or sums of money corresponding to said vouchers would be printed in the second column, the items in the last said column being accumulated as they are recorded.

The principal object of the present invention 40 is to provide means whereby an adding and accumulating machine is adapted for readily accomplishing the above-noted results.

In the accompanying drawings: Figure 1 45 is a side elevation of an adding and accumulating machine constructed in accordance with the present invention; Fig. 2 is an end elevation of the machine; Fig. 3 is a detail view of a portion of the carriage shifting 50 mechanism; Fig. 4 is a plan view of a portion of the machine; Fig. 5 is a plan and

partial sectional view of the operating devices employed for shifting the carriage; Fig. 6 is a longitudinal sectional view through the machine; and Fig. 7 is a skeleton perspective view of part of the machine.

Although the present invention may be embodied in recording and accumulating machines of various forms, it has, for the purpose of illustration, been shown in connection with a machine substantially like that illustrated and described in detail in Letters Patent No. 763,692, dated June 28, 1904.

Referring to the drawings, the frame A 65 carries the operating parts which are suitably connected with and adapted to be actuated from an operating shaft 922, to which, in the form of the machine shown, power is applied by means of a handle B. As the 70 construction, arrangement and operation of the recording and accumulating devices and the connections between the same and the operating shaft 922 are the same as those described in detail in the aforesaid patent, 75 many of such features are herein only generally referred to, particular description being given of the improvements or additional features constituting the invention hereinafter claimed.

The machine includes a plurality of rows 80 of numeral keys 201, a swinging frame D (Fig. 6) carrying adding or accumulating wheels 313, to each of which is connected a pinion 385; and there are slides 404 each 85 connected with a type carrier 403 and provided with a rack 405 with which the pinion 385 of the corresponding member of the accumulating devices may be caused to engage. Movement of the frame D to carry 90 the adding pinions 385 to or from engagement with the racks 405 is effected by operation of a toggle 310 connected through a rod 714 with a swinging arm 710, having a laterally projecting pin 750 extending into 95 the path of shoulders 901^a, 901^b on a vibrating plate 901, mounted on the aforesaid shaft 922. The frame 710 may also be reciprocated, in taking totals and sub-totals, from a link 713 having a notch adapted to 100 engage the pin 750 as said link is lowered. This link is caused to act differently in con-

nnection with the other parts by the adjustment of total and sub-total keys 702^u and 702^r as explained in detail in the patent before referred to.

- 5 The recording mechanism, including the type carriers 403, coöperates with a platen 880 which, as shown in Figs. 1, 2 and 4, is supported by a carriage L of any suitable construction, which carriage is supported to 10 move transversely of the recording devices and to be set in different positions relative thereto to permit of printing items in different columns.

As before stated, it is desirable for many 15 purposes to indicate in one column a series of items without affecting the accumulating devices, and to record in a second column items, positioned in horizontal alinement with those in the first column, the values of 20 which are accumulated on the adding devices as the items are recorded. For instance, the numbers in one column may each 25 indicate a particular article of a series, as boxes, barrels, vouchers, etc., while the item on the same line in the second column will indicate the value in dollars and cents of the 30 article, and the total of the items in the second column will show the value of all the articles represented by the numbers in the first column. In order to obtain this result with a machine of the character illustrated, I provide means whereby movement 35 of the frame D, carrying the adding or accumulating devices, is so controlled that the operating racks 405 will not turn the pinions 385 when the machine is operated with the platen carried out of normal position; or in the position to which it is shifted to cause the printing devices to print in the 40 first said column, while when the machine is operated with the carriage in its normal position the pinions will be actuated by the racks as usual in this class of machines to 45 secure the accumulation of the items recorded in the second said column. I further provide means whereby when the carriage is shifted to bring the platen into position to cause items to be recorded in the column where no additions are to be made, it will 50 not be possible to so adjust the frame D as to secure the taking of a total or a sub-total.

While various means may be employed 55 for accomplishing these purposes I have illustrated an embodiment of the invention in which the platen carriage is normally held in position where each operation of the machine in recording an item will effect an actuation of the accumulating devices, and a shifting handle or element F is provided 60 which is adapted to positively shift the carriage from said normal position; and if the machine is operated to record an item when the carriage has been so shifted, there will be no actuation of the accumulating devices.

55 That is, normally, the carriage will stand in

such relation to the recording devices that items recorded thereby will appear in the column representing values, or the items in which are to be accumulated, while when the machine is operated in the position to which it is shifted by operating the handle F the items will be only recorded and not accumulated. Means are also provided by which the carriage is automatically returned to said normal position following an operation of the machine with the carriage in shifted position, that is, following the movements of the parts of the mechanism caused by or resulting from rocking the shaft 922. When set or moved to carry the carriage from its normal position the handle F shifts parts which act to prevent movement of the frame D necessary to engage the pinions 385 with the racks but has no effect upon the recording devices.

In the adding machine illustrated the parts are normally in the position shown in Fig. 6, the pinions 385 and racks 405 being disengaged, and in operating the machine the desired keys 201 are depressed and the handle B pulled forward, or to the right in Fig. 1. This forward movement of the handle B, as explained in detail in the patent before referred to, properly positions the racks corresponding to rows in which keys have been depressed relative to the adding wheels 313, and as such movement terminates the arm 710 is rocked (by contact of the shoulder 901^a on plate 901 with pin 750) to straighten the toggle 310 and thus move the frame D to cause engagement of the adding wheel pinions and racks 405. The forward movement of the handle also carries the type carriers to printing position and effects a recording of the number represented by the depressed keys.

As the plate 901 swings back in the direction of its arrow, Fig. 6, during the rearward or return movement of handle B, the racks and pinions of the adder wheels are in gear until the shoulder 901^b strikes the pin 750 and breaks the toggle 310 so that the adder wheels accumulate as the type carriers 403 swing from printing position. In order to prevent such accumulation, when a number is to be printed but not added it is only necessary to shift the frame D so as to disconnect the pinions and racks at the beginning of the swing of the plate 901 in the direction indicated by the arrow in Fig. 6, and before the type carriers begin to move toward their normal position; and I provide means whereby this disconnecting of the pinions and racks is effected by the adjustment of the operating handle F, which is connected to shift the carriage to the position where the numbers which do not represent values should be printed. One means of securing this disconnection of the pinions from the racks, before the latter and their

connected type carriers begin to move to their normal, inactive, positions, consists in putting under tension a spring 22, Figs. 1 and 6, and causing it to bear upon the arm 710, so that the latter will be moved to the rear as soon as the shoulder 901^a is carried to the rear from engagement with pin 750.

As shown, the spring 22 is carried by an arm 21, which is connected by a link 25 with the lower end of the lever F, which is carried by a rock shaft 1 so that when the lever F is set to the position indicated by the dotted line x, Fig. 6, the spring 22 will bear under tension against the arm 710, which will therefore swing to the rear as soon as the plate 901 begins to rock to carry the shoulder 901 to the rear.

The setting of the lever F to the forward position described is utilized for shifting the carriage to that position which it should occupy for printing those items which are not to be added. Different means for thus moving the carriage from the lever may be employed, but, as shown (Figs. 2, 5 and 7) the shaft 1 carries an arm 2 which extends above an arm 3 pivoted to the frame of the machine at one end and connected at the other to a link 4 which in turn is connected to an arm 5 on a rock shaft 6 provided at the rear of the machine with an arm 7 which bears upon a bearing of the platen carrier L. As a result, when the lever F is moved in the direction of its arrow, Fig. 7, the shaft 6 will be rocked in the direction of its arrow and the carriage shifted. As shown, the bearing upon the carriage consists of the pintle of a knob K which is adjustable to different positions in a slot y, Fig. 2, formed in a member of the carriage, to thereby enable the extent of movement imparted to the carriage to be varied. In order that the carriage may be held in the position to which it is thus set by a forward movement of the lever F I make use of a suitable device as, for instance, a catch 31 (Fig. 7) having a projection adapted to enter a notch 33 in an arm 34 extending from the shaft 6, when the latter is turned to the position required for properly setting the carriage L. To the catch 31 is pivoted a dog 36 which projects beyond the end of the catch and bears at its inner end against the pin 37 of the catch, a spring 38 tending to hold the dog in this position and also to lift the catch 55 so as to engage the arm 34.

On the plate 901 is a stud 39 (see Fig. 6) which simply swings the dog 36 away from the stud 37 when the plate 901 swings in the reverse direction of that indicated by its arrow in Fig. 6, and which is not affected by the swinging of the arm 34 into locking relation with the catch. However after the printing has been effected on the backward movement of the plate 901 in the direction 65 of its arrow, the lug 39 will be brought in

contact with the end of the dog 36 and the catch 31 depressed so as to release the arm 34, and the shaft 6 will be rocked in the direction of its arrow, Fig. 2, by the action of a spring 40 connected with the lever F, and acting to carry it and parts connected therewith to normal position.

In the ordinary operation of the machine reciprocation of the operating shaft 922 results in the rocking of a shaft 50 (Fig. 1) 75 upon the carriage, said shaft being connected to a link or bar 811 adapted to be actuated by an arm (not shown) on the shaft 922. The shaft 50 carries a pivotally mounted pawl 51, adapted to engage a ratchet 52 80 upon the shaft of the platen 880. It will be evident that where an item is first to be printed in one column and thereafter another item is to be recorded upon the same horizontal line in another column, the platen should not be rotated to feed the paper until the second item has been printed. I therefore provide means whereby the feeding devices are rendered inoperative upon the platen until the second of two items to be printed in the same horizontal line has been recorded. As shown a shaft 53, carried by the carriage, is provided with an arm 54, and the arm 55 on the rock shaft 50, to which the pawl 51 is pivoted, has a stud 56 so arranged as to be engaged by the arm 54 when the latter is depressed. The arm 54 operating upon the pin 56 will act to move arm 55 and thereby carry the pawl 51 from the platen ratchet and into such position that 100 when the shaft 50 is rocked it will not effect a turning of the platen and therefore there will be no feeding of the paper when the machine is operated with the arm 54 in its shifted, depressed, position.

I provide means whereby the shaft 53 is rocked to depress the arm 54 as the handle F is drawn forward. The said means (Figs. 2 and 3) consists of a slide 60 provided with studs 61 entering inclined slots 62 in the 110 frame of the carriage and extending beneath an arm 63 on the rock shaft 53, and this slide carries the knob or bearing K so that when the arm 7 makes contact with the pintle of said knob the first action will be to 115 move the slide 60 to the left and upward, Fig. 2, raising the arm 63 and rocking the shaft 53 to bring its arm 54 in position to prevent the pawl 51 from turning the ratchet 52. When the arm 7 rocks back a spring 70, 120 hereinafter referred to, carries the slide to the right and restores the parts to normal position.

Preferably the carriage, after being shifted as a result of drawing forward the handle F, and after the printing in the non-adding column takes place, is restored automatically to its normal position. This results from the releasing of the catch 31, permitting the carriage to move back under the 130

action of spring 70, one end of which is connected with a stud or post on the frame of the machine, the other end being attached to a projection on the member 75 of the platen carriage as shown in Fig. 4.

To prevent the slide 60 from moving back immediately after the arm 7 begins to swing in the direction of its arrow, Fig. 2, I provide a swing-actuated pawl 71, which when 10 the slide is carried fully to the left will engage a shoulder 72 of the slide 60, and as the carriage returns to its normal position, the tail of the pawl 71 will contact with the stud 73 and the pawl will be tilted so as to 15 release the slide which is adjusted by a spring to cause the studs 61 thereon to move downwardly in their guiding slots.

As explained in the patent hereinbefore referred to, and from the foregoing description, it will be seen that each actuation of the shaft 922 effects a reciprocation of the cam 901 and movement of the parts actuated or controlled thereby. In the particular embodiment of the invention herein 25 illustrated the shaft 922 is moved by the operating handle B, hereinafter referred to as a "manually movable element", which is connected with the shaft 922 by a link 91 and plate-like arm 92 hereinafter more particularly referred to. The result of such movements when the platen has been shifted by the operation of the handle F is to release the catch 31, and automatically the platen and paper feeding devices are 30 stored to normal position.

As it is sometimes desirable to print the columns upon the sheet at different distances from the edge or margin thereof I provide means whereby the platen or parts carrying 40 the same may be adjusted to different positions in respect to the devices for shifting the carriage from the handle F. One means of securing this result (shown particularly in Figs. 2, 4 and 5) consists in connecting 45 the member 75 of the carriage, with which the slide 60 co-operates, adjustably to the main frame. As shown, the part 75 is a plate having slots for the passage of guiding bolts or studs 76, 73 and provided also 50 with one or more notches 12 adapted to receive a finger or arm 10 upon a shaft 9 rocking in the carriage frame and provided with a lever 78, by shifting which the shaft 9 may be rocked to lift the finger 10 out of one of 55 the notches, after which the main body of the carriage may be moved longitudinally to a position for the finger to enter another notch. A spring 79, connected with the lever 78, tends to rock the latter and the 60 shaft 9 to maintain the finger in the notch in which it is placed.

In order to prevent any possible manipulation of the total or sub-total keys when the carriage has been moved to a position to 65 print in the non-adding column, I provide

the arm 21 with an extension having a lateral flange 80 (Figs. 4 and 6) which, when the said arm is carried backward, is brought beneath the end of the link 713, to prevent the descent of the latter and its engagement with the pin 750. As such engagement is essential to the totalizing operation, the latter is prevented until the carriage is restored to its normal position. In order also to prevent the operation of the handle B, or other starting device, after the handle F begins its movement, and until such movement and the movement of the carriage is completed, I provide parts which are shifted on the movement of the handle F 70 to such a position as to prevent any movement of the operating parts until the movement of the handle F has been completed. As shown best in Fig. 7, the handle B is connected to a short shaft 90, a pin on which 75 enters a slot in connecting bar 91, which is pivoted to the full motion segment 92 carried by the shaft 922. On the bar 91 is a stop 93. A short shaft 94, turning in bearings in the main frame, carries a dog 95 which may be set on swinging handle F so as to be in the line of movement of the stud 93, except when the said handle is in one of its extreme positions. While different connections may be employed, I show a rock shaft 96 turning in bearings in the frame and having a slotted arm 97 engaging a pin 98 projecting from the arm 2 and carrying another arm 99 from which is pendent a slotted link 100 receiving a pin 101 upon an arm 102 on the 80 rock shaft 94. A spring 103 tends to rock the dog 95 to the position shown in Fig. 7, which is the normal position when the machine is operating to add, but as soon as the handle F begins its movement in the direction of the arrow, the link 100 is thrust downward and swings the end of the dog 95 to a position to contact with the stud 93, and until the handle is at the end of its forward movement the dog 95 will be in position to 85 make contact with the stud 93. When, however, the handle F is fully forward, the end of the dog 95 will be below the line of movement of the stud 93 and the handle B can 90 then be operated.

It will thus be seen that by the present invention the platen carriage may be longitudinally adjusted on the frame of the machine and secured in the desired adjusted position by engagement of the finger 10 with the proper notch 12; and the machine may be operated to record items represented by keys depressed on the keyboard in either one or two columns when the carriage is in any of the said positions.

When items are recorded in two columns the platen carriage is positively shifted from its normal position by operation of the handle F and automatically returned to such normal position, after the operation of the 100

machine with the carriage and platen in such shifted position, by the power stored in the spring 70 during the shifting by the handle F. It will also be noticed that if the machine is operated to record items in two columns there will be no rotary or paper-feeding movement imparted to the platen when the machine is operated in its shifted position (that is, in the position where actuation of the accumulating devices is prevented) but that such rotary or paper-feeding movement will be imparted to the platen at the conclusion of an operation of the machine with the carriage in normal position.

15 By the invention it is possible to employ the full capacity of the machine for recording items in either, or both, of two columns and thereby to secure results which could only be accomplished, if at all, with adding 20 machines as heretofore constructed having twice the number of keys, type carriers, etc. That is, the full capacity of the machine is, by this invention, made available for both recording without accumulating and for simultaneously recording and accumulating.

25 Having thus described the invention, what is claimed and desired to be secured by Letters Patent is:

1. In a machine of the character described, 30 the combination of recording devices, accumulating devices, paper - feeding devices, a manually movable element controlling all said devices, a platen movable relative to the recording devices to permit items to be recorded in different columns, means for holding the platen in a position where each of a succession of actuations of said manually 35 movable element may effect an actuation of the recording, accumulating and paper-feeding devices, the items being all recorded in one column, means for shifting the platen from such position, and means whereby when the platen is shifted from such normal position to permit items to be recorded in another column actuation of said manually 45 movable element cannot effect an actuation of the accumulating or paper-feeding devices.

2. In a machine of the character described, 50 the combination of recording devices, accumulating devices, a rotatable platen movable relative to the recording devices to permit items to be recorded in different columns, a manually movable element controlling the 55 recording and accumulating devices, means for holding the platen in the position where each of a succession of actuations of said manually movable element may effect actuation of the recording, accumulating and 60 platen rotating devices, all items recorded by such actuations being in one column, means for shifting the platen from such position, and means whereby when the platen is shifted from such normal position to permit items 65 to be recorded in another column actuation

of said manually movable element cannot effect actuation of the accumulating and platen rotating devices.

3. In a machine of the character described, the combination of recording devices, accumulating devices, a manually movable element controlling both the recording and accumulating devices, a platen, means independent of said manually movable element adapted to shift the platen longitudinally to 70 permit items to be recorded in different columns, means for holding the platen in position to cause items to be recorded in one column, means for shifting the platen from such normal position, and means whereby 75 when the platen is shifted from its normal position to permit the recording of an item in another column actuation of such manually movable element will not effect actuation of the accumulating devices.

4. In a recording and accumulating machine, the combination with recording devices, accumulating devices, a manually movable element controlling said recording and accumulating devices, and a platen mounted 90 to move longitudinally relative to the recording devices to permit items to be recorded in different columns, of adjustable means for moving said platen from one position to another to vary the distance between two columns, means for actuating both the recording and accumulating devices when said manually movable element is actuated with the platen positioned to cause the items to be recorded in one column, and means for preventing 95 actuation of the accumulating devices when said element is actuated with the platen in position to cause items to be recorded in the other column.

5. In a recording and accumulating machine, the combination with recording devices, accumulating devices, a manually movable element controlling the recording and accumulating devices, and a platen mounted to move past the recording devices, of means 100 for shifting said carriage to adjust the platen relative to the recording devices and permit items to be recorded in different columns comprising a rock shaft, an arm carried by said shaft and engaging the platen carriage, 105 and means for rocking said shaft, and means for preventing actuation of the accumulating devices when said manually movable element is operated with the platen in position to have items recorded in one of said columns.

6. In a recording and accumulating machine; the combination with recording devices, accumulating devices, a manually movable element controlling the recording and accumulating devices, and a platen mounted 115 to move past the recording devices, of means for shifting said carriage to adjust the platen relative to the recording devices and permit items to be recorded in different columns comprising a rock shaft, an arm car- 120

- ried by said shaft, a stud adjustably mounted on the carriage and extending into the path of movement of said arm, and means for rocking the shaft, and means for preventing actuation of the accumulating devices when the said manually movable element is operated with the platen in position to have items recorded in one of said columns.
10. 7. In a recording and accumulating machine, the combination with recording devices, accumulating devices, a carriage, and a platen mounted on the carriage to move past the recording devices, of means for shifting said carriage to adjust the platen relative to the recording devices and permit items to be recorded in different columns comprising a rock shaft, an arm carried by said shaft and engaging the platen carriage, and means for rocking said shaft, a spring for moving the platen in a direction opposite that in which it is moved by said rock shaft, and means for preventing actuation of the accumulating devices when an item is recorded by the machine with the platen in the position to which it is moved by rocking said shaft.
15. 8. In an adding machine, the combination with printing devices, and a platen mounted to move longitudinally relative to the printing devices to permit items to be recorded in different columns, of means operable by hand for shifting said platen longitudinally at each movement of said means, and means for automatically returning the platen to its former position after an operation of the printing devices with the platen in such shifted position.
20. 9. In an adding machine, the combination with printing devices, and a platen mounted to move longitudinally relative to the printing devices to permit items to be recorded in different columns, of means operable by hand to positively shift the platen longitudinally, adjustable devices adapted to vary the extent of such movement of the platen, and means for automatically returning the platen to its former position after an operation of the printing devices with the platen in such shifted position.
25. 10. In an adding machine, the combination with printing devices, a sliding platen carriage, and a platen on said carriage, of means operable by hand for shifting the carriage in one direction, means for automatically moving the carriage in the opposite direction after an operation of the printing devices with the carriage in its shifted position, and means for adjusting the platen to different positions in respect to said shifting means.
30. 11. In an adding machine, the combination with printing devices, a manually movable element adapted to effect operation of the printing devices, a sliding platen carriage, a platen on the carriage, and means for rotating the platen, adapted to be normally actuated at each actuation of said manually movable element, of means for shifting the carriage relative to the printing devices, means for preventing operation of the platen rotating devices when the carriage is in said adjusted position, means for holding the carriage in said adjusted position until said manually movable element is operated, and means for automatically returning the carriage to its former position after such operation of said manually movable element.
35. 12. In an adding machine, the combination with printing devices, a sliding platen carriage, a platen on the carriage, and means for rotating the platen, adapted to be normally actuated at each operation of the printing devices, of means for shifting the carriage relative to the printing devices, means for preventing operation of the platen rotating devices when the carriage is in said adjusted position, a lock for holding the carriage in such adjusted position, and means for automatically releasing said lock and restoring the carriage to normal position after the next operation of the printing devices.
40. 13. In a recording and accumulating machine, the combination of recording devices, accumulating devices, a sliding platen carriage movable past the recording devices to permit items to be recorded in different columns, a rock shaft, means on said shaft adapted to shift the platen carriage, means for locking the carriage in said shifted position, means for actuating the accumulating devices when an item is recorded with the platen carriage in its normal position, means for preventing actuation of the accumulating devices when the carriage is in said shifted position, means for releasing said lock when an item has been recorded with the carriage in its shifted position, and means for automatically restoring the carriage to normal position.
45. 14. In a recording and accumulating machine, the combination of recording devices, a manually shiftable element controlling said recording devices, a rotatable platen adapted to be adjusted longitudinally past the recording devices to permit items to be recorded in different columns, means for shifting the platen longitudinally, a ratchet and pawl mechanism for rotating the platen, means for actuating said mechanism to turn the platen at each operation of said manually movable element when the platen is in normal position, and means for adjusting said ratchet and pawl mechanism as the platen is shifted longitudinally, whereby the platen will not be turned when said manually movable element is operated with the platen in said shifted position.

15. In a recording and accumulating machine, the combination of recording devices, a mutually movable element controlling said recording devices, a rotatable platen adapted to be adjusted longitudinally past the recording devices to permit items to be recorded in different columns, means for shifting the platen longitudinally, a ratchet connected with the platen, a pawl adapted to be moved at each operation of said mutually movable element and to engage and turn the platen when the latter is in its normal position, a swinging arm adapted to adjust said pawl so that it will not actuate said ratchet when the machine is operated, and means for automatically swinging said arm to adjust the pawl as aforesaid when the platen is shifted longitudinally from its normal position. 70
16. In a recording and accumulating machine, the combination of recording devices, accumulating devices, a platen movable relative to the recording devices to permit items to be recorded in different columns, a hand operated device for thus shifting the platen, and means for preventing operation of the recording or accumulating devices while the platen is being shifted. 75
17. In an adding machine, the combination with printing devices adapted to print at one operation a number comprising a plurality of digits and a platen mounted to be adjusted longitudinally relative to the printing devices, of means for reciprocating the platen adapted to be manually operated to move the platen in one direction and automatically operated to move the platen in the opposite direction following an operation of the printing devices with the platen in its shifted position. 80
18. In an adding machine, the combination with printing devices adapted to print at one operation a number comprising a plurality of digits, and a platen mounted to be adjusted longitudinally relative to the printing devices, of means for reciprocating the platen including hand actuated devices for moving it in one direction and power devices, rendered operative by such movement, for moving the platen in the opposite direction. 85
19. In an adding machine, the combination with printing devices and a platen adapted to be adjusted longitudinally past the printing devices to any desired one of a plurality of positions, of means for reciprocating the platen longitudinally to and from any of said normal positions and holding it stationary at either end of such reciprocation during an operation of the printing devices. 90
20. In an adding machine, the combination with printing devices, a platen, the printing devices and platen being relatively adjustable to bring any one of a plurality of sections of the platen in alignment with the printing devices, and means for feeding paper between the platen and the printing devices, of independent means for reciprocating the platen to and from any of said normal positions, and means for preventing actuation of the paper feeding devices when the printing devices are operated with the platen one limit of such reciprocating movement. 95
21. In an adding machine, the combination with printing devices, a platen, the printing devices and platen being relatively adjustable to bring any one of a plurality of sections of the platen in alignment with the printing devices, and means for feeding paper between the platen and printing devices adapted to be automatically actuated when the printing devices are operated with the platen in any of its said positions, of means for shifting the platen longitudinally and retaining it in such shifted position during an operation of the printing devices, and means for preventing actuation of the paper feeding devices when the printing devices are operated with the platen in other than normal position. 100
22. In an adding machine, the combination with printing devices, a platen, the printing devices and platen being relatively adjustable to bring any of a plurality of sections of the platen in alignment with the printing devices, and means for feeding paper between the platen and printing devices adapted to be automatically actuated when the printing devices are operated with the platen in any of its said positions, of means under the control of the operator for shifting the platen longitudinally in one direction from any of said normal positions and rendering the paper feeding devices inoperative, and means for automatically returning the platen to normal position after an operation of the printing devices with the platen in shifted position. 105
23. In an adding machine, the combination with printing devices, a platen, and means for rotating the platen to feed paper, between it and the printing devices and adapted to be automatically actuated when the printing devices are operated, of means for shifting the platen longitudinally and rendering the platen rotating devices inoperative when the printing devices are operated with the platen in such shifted position, and means for automatically returning the platen to normal position after an operation of the printing devices with the platen in its shifted position. 110
24. In an adding machine, the combination with printing devices, a platen, and means for rotating the platen including a ratchet connected with the platen and a pawl adapted to engage said ratchet and to be automatically moved at each operation. 115
25. In an adding machine, the combination with printing devices, a platen, the printing devices and platen being relatively adjustable to bring any one of a plurality of sections of the platen in alignment with the printing devices, and means for feeding paper between the platen and the printing devices, of independent means for reciprocating the platen to and from any of said normal positions, and means for preventing actuation of the paper feeding devices when the printing devices are operated with the platen one limit of such reciprocating movement. 120
26. In an adding machine, the combination with printing devices, a platen, the printing devices and platen being relatively adjustable to bring any one of a plurality of sections of the platen in alignment with the printing devices, and means for feeding paper between the platen and the printing devices, of independent means for reciprocating the platen to and from any of said normal positions, and means for preventing actuation of the paper feeding devices when the printing devices are operated with the platen one limit of such reciprocating movement. 125
27. In an adding machine, the combination with printing devices, a platen, the printing devices and platen being relatively adjustable to bring any one of a plurality of sections of the platen in alignment with the printing devices, and means for feeding paper between the platen and the printing devices, of independent means for reciprocating the platen to and from any of said normal positions, and means for preventing actuation of the paper feeding devices when the printing devices are operated with the platen one limit of such reciprocating movement. 130

- of the printing devices, of means for shifting the platen longitudinally, and means for preventing engagement of said pawl and ratchet when the platen is in its shifted position.
25. In an adding machine, the combination with printing devices, a platen, and means for rotating the platen including a ratchet connected with the platen and a pawl adapted to engage said ratchet and to be automatically moved at each operation of the printing devices, of means for shifting the platen longitudinally, means for preventing engagement of said pawl and ratchet when the platen is in its shifted position, and means for automatically returning the platen to normal position and permitting re-engagement of said pawl and ratchet after an operation of the printing devices with the platen in the shifted position.
26. In an adding machine, the combination with printing devices, a platen, and means for rotating the platen including a ratchet connected with the platen and a pawl adapted to engage said ratchet and to be automatically moved at each operation of the printing devices, of means for shifting the platen longitudinally, means for rocking and holding said pawl from engagement with said ratchet as the platen is thus shifted and means for releasing the pawl as the platen is returned to normal position.
27. In an adding machine, the combination with printing devices, a platen, means for feeding paper between the platen and printing devices, and a manually movable element controlling operation of said printing and paper feeding devices, of manually operable means for shifting the platen longitudinally and rendering the paper feeding devices inoperative while the platen is in such shifted position, means for holding the platen in such shifted position until the manually movable element is operated, and means for restoring the platen and paper feeding devices to normal position and relation after an operation of said manually movable element with the platen in its shifted position and by power produced by the shifting of the platen.
28. The combination with a platen, printing devices adapted to coöperate with the platen, the latter being adapted to be adjusted transversely of the printing devices to permit items to be recorded in different columns, and means for feeding paper between the platen and printing devices; of means for holding the platen in the same position relative to the printing devices during successive operations of the latter, whereby items will be recorded in a single column, means for actuating the paper feeding devices whenever the printing devices are operated with the platen in such position, means independent of those actuating the printing devices for shifting the platen transversely of the printing devices, and means for preventing actuation of the paper feeding devices with the printing devices when the platen is in such shifted position, said means being automatically rendered inoperative when an item is recorded with the platen in said shifted position.
29. The combination with a platen and printing devices coöperating with the platen, the latter being adjustable to move a sheet of paper transversely and longitudinally between itself and the printing devices, of means for automatically adjusting the platen to feed the paper longitudinally when the printing devices are operated, means independent of those aforesaid for adjusting the platen and paper transversely of the printing devices, and means for preventing adjustment of the platen to effect longitudinal feed of the paper when the printing devices are actuated with the platen in such adjusted position.
30. The combination with a platen, and printing devices coöperating with the platen, the latter being adapted to be adjusted transversely of the printing devices to permit items to be recorded in a plurality of columns, and means for feeding paper between the platen and printing devices, of means for actuating the paper feeding devices whenever the printing devices are operated with the platen in position to cause items to be recorded in one column, means independent of those actuating the printing and paper feeding devices for shifting the platen to permit recording in another column, and means for preventing actuation of the paper feeding devices when the platen has been thus shifted until the printing devices have been operated to record items in two columns.
31. The combination with a platen, and printing devices coöperating with the platen, the latter being adapted to be adjusted transversely of the printing devices to permit items to be recorded in a plurality of columns, and means for feeding paper between the platen and printing devices, of means for actuating the paper feeding devices whenever the printing devices are operated with the platen in position to cause items to be recorded in one column, means independent of those actuating the printing and paper feeding devices for shifting the platen to permit recording in another column, and means for automatically restoring the platen to its aforesaid normal position after an operation of the printing devices with the platen in shifted position.
32. The combination in a recording mechanism, of a frame, a carriage sliding longitudinally thereon, a platen on said carriage, means for printing upon a sheet carried by the platen, a slide movable longitudinally

on the frame, means connecting the slide and carriage, a shaft, and connections between said shaft and slide for sliding the latter.

33. The combination with the frame, platen carriage and operating handle of a recording mechanism, of a slide sliding on the frame and adapted to be actuated by the handle and provided with means for engaging the carriage.

34. The combination with the frame, platen carriage and operating handle of a recording mechanism, of a slide sliding on the frame and adapted to be actuated by said handle and provided with means for engaging the carriage, said slide and carriage being relatively adjustable and adapted to be connected by said means in different adjusted positions.

35. The combination with the frame, platen carriage, and operating handle of a recording mechanism, of a notched slide sliding on the frame and adapted to be actuated by said handle, and means on the carriage for engaging said notched slide. 25

36. The combination with the frame, platen carriage, and operating handle of a recording mechanism, of a notched slide sliding on the frame and adapted to be actuated by said handle, said carriage being 30 provided with a movable member adapted to engage any of the notches in said slide.

In testimony whereof I affix my signature in presence of two witnesses.

WILLIAM H. PIKE, Jr.
